UNITED STATES PATENT OFFICE.

ALBERT W. WINSHIP, OF UTICA, NEW YORK.

TRUNK.

1,115,362.

Specification of Letters Patent. Patented Oct. 27, 1914.

Application filed October 26, 1911. Serial No. 656,883.

To all whom it may concern:

Be it known that I, ALBERT W. WINSHIP, of Utica, in the county of Oneida and State of New York, have invented certain new and useful Improvements in Trunks; and I do hereby declare that the following is a full, clear, and exact description thereof, which will enable others skilled in the art to which it appertains to make and use the same, reference being had to the accompanying drawings, and to the reference numerals marked thereon, which form part of this specification.

The purpose of my present invention is to provide an improved combined wardrobe and general trunk having certain features that render the trunk stronger in construction and more convenient in use.

One object is to provide a trunk of this class that is so constructed that it may be readily opened to such an extent that the clothes or other articles therein may be quickly and readily accessible.

Another object is to provide a construction of few movable parts and these of such simplicity that anyone can operate them without danger of disconnecting them or assembling them in the wrong way.

Another object is to provide in addition to the wardrobe section a chiffonier compartment preferably equipped with drawers which may be reached without disturbing the wardrobe section whether that section be open or shut and which chiffonier compartment may be left shut or open or may be opened or closed again without regard to the condition of the wardrobe section. The construction is such, however, that each section strengthens the other and cooperates to form a trunk of great strength, durability, convenience and adaptability.

A further object is to provide in this class of trunks a construction whereby either or both sections may be opened without moving the trunk bodily or either section thereof.

Although the trunk is opened up to a much greater extent than usual, the trunk case and its openings and closures and internal partitions are all so constructed and arranged with regard to each other as to guard against the weaknesses and lack of rigidity usual in such a trunk.

Figure 1 is a perspective view of a trunk embodying my invention. Fig. 2 is a perspective view of the same on a slightly en-

larged scale when opened. Fig. 3 is a horizontal sectional view across the trunk just below the top and top closure.

Referring to the drawings in a more particular description, the trunk casing consists of a bottom 9 to which are secured two whole sides 10 and 11 adjacent to each other and an internal partition 12 parallel to side 11 and secured to side 10 and dividing the trunk perpendicularly into two compartments, 13 and 14 which I will respectively designate the wardrobe compartment to the left as seen in Fig. 2 and the chiffonier compartment to the right as seen in Fig. 2. Further fixed parts of the trunk are a half-side 15 rising from the bottom 9 and secured to the near side edge of the partition 12 as seen in Fig. 2, and a half-top 16 secured to the top edges of the side 11, the partition 12 and that portion of the side 10 between the partition 12 and the side 11. It will be seen that this construction leaves the broad outer side and the top of the wardrobe compartment entirely open and also one narrow side of the chiffonier compartment open. For the latter opening there is provided a closure 17 perpendicularly hinged to the half side 15 along the line of its contact with the adjacent edge of the internal partition 12. This closure has valance strips 18 and 19 projecting at right angles from its top and free side respectively so as to overlap against the outside of the adjacent edges of the half top 16 and the side 11 when this closure is closed. From the lower edge of the closure 17 projects downwardly a valance strip 20 adapted to overlap the outside of the bottom at 21 which here extends upward for that purpose and far enough so that the bottom edge of the closure 17 with its lower valance strip will swing clear of the floor. Spring catches 22 and a lock 23 of any desired form are provided for securely holding the closure shut against the trunk casing.

To close the side opening of the wardrobe compartment 13 there is provided a closure 24 perpendicularly hinged to the side 10 and having on each side edge valance strips 25 and 26 projecting at right angles from said closure edges to overlap the edges of the sides 10 and 15 respectively. From the lower edge of this closure projects downward a valance strip 27 to overlap the outside of the bottom at 28 which here extends upward for that purpose and far enough so

that the bottom of the closure with its downwardly extending valance strip will swing clear of the floor as it is opened.

To close the top opening of the wardrobe 5 section, there is provided a closure 29 horizontally hinged to the half-top 16 along the line of its contact with the upper edge of the partition 12. From the free edges of this closure there project at right angles 10 thereto valance strips 30, 31, and 32 to overlap the upper edges respectively of the side 10, side 15 and side closure 24.

Spring catches 22 secure the free side edge 15 of the closure 24 to the side 15 and the edge 10 of the top closure to the overlapped top edge of the side closure 24. A lock 33 having its two members upon the adjacent edges 20 of the top closure 29 and side closure 24 provides means for locking the wardrobe section.

It will now be apparent that the entire 25 trunk stands upon one solid bottom and that either or both compartments can be opened without having to move the trunk or either 30 compartment; also that the chiffonier compartment may be opened, left open, shut again or left entirely closed without regard to the condition of the wardrobe compartment; also that the wardrobe compartment 35 can be opened, left open, shut again or left entirely closed without regard to the condition of the chiffonier compartment.

The chiffonier compartment may be provided with drawers or other containers 34 35 which may be readily withdrawn therefrom through the side opening therein.

It will be further noticed that though the trunk has a great area of openings, yet these 40 openings and the fixed trunk casing, the internal partition and the closures are all so arranged and constructed as to give great strength and rigidity to the entire trunk; particularly that the single internal partition is so arranged as to leave only one opening 45 in the chiffonier compartment and that on its narrow side, and forms a brace centrally located in the trunk to stiffen it and particularly to form a solid back tying together both sides and the bottom of the wardrobe 50 compartment and so bracing the sides and bottom from any spreading. This partition is secured at about the center of the bottom and the side 10, it thereby gives those parts the stiffness of the material therein instead 55 of simply the stiffness of the corner fastening. It will be further noted that this internal partition affords the strength of its angular contact with the half-top 16 and the half-side 15 for the rigid and strong hinging 60 of the closures 29 and 17 respectively. This arrangement prevents any tendency of these closures to spring themselves or the part to which they are hinged, and adding strength to said closures and the whole 65 trunk as the edges of these closures oppo-

site their hinged edges form external corner edges of the trunk when closed.

Around the inside of the wardrobe compartment extends a U-shaped metal strip 35 having its loop portion fastened to the partition 12 and its ends extended nearly to the front edges of the sides 10 and 15 and securely fastened thereto. This strip further strengthens the upper forward corners of the sides 10 and 15 and its loop portion affords a secure anchorage for the bent inner ends 36 of a pair of slideways 37 horizontally arranged and spaced a short distance from either side of the wardrobe compartment and extending to the front or open 70 side thereof. Just back from the outer end of each of these slideways 37 there is rigidly fastened a brace 38 which extends downwardly and outwardly in a diagonal direction to the adjacent side of the compartment to which it is rigidly secured. To the free end of each of these slideways is perpendicularly hinged an extension slideway 39 by means of a deeply interlocking 75 rule joint formed from intermeshing projections formed integral with the slideway 37 and the extension slideway 39, through which projections a joint pin 40 is inserted. The joint is adapted to stop the extension 80 when it has been swung straight out into line with the fixed slideway as shown in Figs. 2 and 3 and to allow the extension to be swung around horizontally to a position 85 entirely within the wardrobe compartment 90 as indicated in dotted lines in Fig. 3 and allow the side closure thereof to be closed. Over these slideways fit and slide notched cross-pieces 41 to which are secured clothes-hangers 42 of any desired form allowing the 95 clothes to be drawn out from the wardrobe 100 compartment and be suspended upon the extension slideways without the wardrobe 105 compartment and where they can be easily seen or removed.

Upon the slideways is slidingly mounted a 110 clothes retaining rack formed of uprights 43 and cross-pieces 44 and sliding clutches 45 adapted to allow the rack to be slid back and forth upon the slideways 37 and 39 and to hold the rack in any position on said 115 slideways without any further operation. Each clutch 45 is of metal and has a strap portion 46 for securing it firmly to the upright 43 of the rack and in its body portion has an opening of the shape and substantially the size of the slideway in cross-section and so that the clutch encircles the slideway on its upper and inner side entirely and partly on the outer and lower side as plainly seen in Fig. 4. This arrangement 120 prevents the rack from being removed from the slideways in any way except from the outer ends thereof. The outer ends of the extension slideways are turned upwardly 125 in the shape of hooks 48 which prevent the 130

rack from slipping off of the slideways when pulled out in the ordinary way but allow the rack to be removed by moving its lower end outwardly and upwardly so as to let the 5 clutch ride around the upward curve of the hook 48.

In operation the wardrobe closures 24 and 29 are opened, the extension slideways 10 swung out into extended position and the clothes retaining rack moved out onto the extension slideways by first pressing inwardly upon the lower part of the rack. The rack may be then entirely removed from the slideways as heretofore described 15 and the clothes hangers slid off of the ends of the extension or the rack may be left at the outer end of the extensions and the clothes hangers slid out part way and then lifted up taking the clothes up between the 20 extensions.

What I claim as new and desire to secure by Letters Patent is:

1. A trunk adapted to stand on end when opened consisting of a bottom, two adjacent 25 sides, a perpendicular partition parallel to one of said sides and secured to the other side and dividing said trunk into wardrobe and chiffonier compartments, a top for said chiffonier compartment leaving one narrow 30 side open, a narrow side for the wardrobe compartment leaving the outer broad side and the top of said compartment open, a closure for said broad side of the wardrobe compartment and closures hinged along the 35 edge of the said central partition for said top opening of the wardrobe compartment and for the side opening of the chiffonier compartment, said closure for said chiffonier compartment being adapted when 40 opened to fold back flat against the narrow side of the wardrobe compartment.

2. A trunk adapted to stand on end when opened consisting of a bottom, two adjacent 45 sides, a perpendicular partition parallel to one of said sides and secured to the other side and dividing said trunk into wardrobe and chiffonier compartments, a top for said chiffonier compartment leaving one narrow 50 side of said compartment open, a narrow side for the wardrobe compartment leaving the outer broad side and the top of said 55 compartment open, a closure for said broad side of the wardrobe compartment, closures hinged along the edge of said central partition for said top opening of the wardrobe compartment and for the side opening of the chiffonier compartment, said closure for said chiffonier compartment being adapted when 60 opened to fold back flat against the narrow side of the wardrobe compartment, garment-hanger supports upon the permanent walls of said wardrobe compartment near the top thereof and garment hangers

removable through the top opening of said wardrobe compartment when said top closure is open. 65

3. A trunk adapted to stand on end when opened consisting of a bottom, two adjacent 70 sides, a perpendicular partition parallel to one of said sides and secured to the other side and dividing said trunk into wardrobe and chiffonier compartments, a top for said chiffonier compartment leaving one narrow 75 side of said compartment open, a narrow side for the wardrobe compartment leaving the outer broad side and the top of said compartment open, a laterally hinged closure for the opening of the wide side of said wardrobe compartment, a closure for the top opening of the wardrobe compartment 80 hinged along the top of said central partition and having a valance strip overlapping the top edge of the aforesaid side closure and a closure for the narrow side opening of said chiffonier compartment hinged along 85 the edge of the said central partition, said closure for said chiffonier compartment being adapted when open to fold back flat against the narrow side of the wardrobe 90 compartment.

4. A trunk adapted to stand on end when opened consisting of a bottom, two adjacent 95 sides, a perpendicular partition parallel to one of said sides and secured to the other side and dividing the said trunk into wardrobe and chiffonier compartments, a top for said chiffonier compartment leaving one narrow side of said compartment open, a narrow side for the wardrobe compartment leaving the outer broad side and the top of 100 said compartment open, a laterally hinged closure for the opening of the wide side of said wardrobe compartment having valance strips overlapping adjacent parts at both sides and the bottom, a closure for said top 105 opening of the wardrobe compartment hinged along the top of said central partition and having valance strips overlapping both stationary sides and the top edge of the aforesaid side closure and a closure for 110 said narrow side opening of the chiffonier hinged along the edge of the said central partition and having valance strips on its other sides overlapping adjacent parts, said closure for said chiffonier compartment being adapted when opened to fold back flat 115 against the narrow side of the wardrobe compartment.

In witness whereof I have affixed my signature, in the presence of two witnesses, this 120 18th day of October, 1911.

ALBERT W. WINSHIP.
